VINCENT J. LOUGHLIN, OF KENMORE, NEW YORK

TACKLING DUMMY

Application filed March 30, 1932. Serial No. 602,070.

My invention relates in general to tackling dummies, and in particular to that type of dummy used in the practice of football.

It is well known to those skilled in the art that the dummies used at present are usually of rigid, one-piece construction, which not only are likely to cause injury to the player, and therefore affect the accuracy and enthusiasm of his play, but which can be used only in one position and can not be placed in the necessary positions to give full and complete instruction and practice in the game of football.

One of the objects of my invention has been to provide a dummy which shall duplicate very closely the physical reactions of the human body when tackled or blocked.

Another object has been to provide a dummy so constructed that it may be set up to simulate the position of an opponent in running, standing, or crouching attitudes.

Furthermore, my dummy is so constructed that it can be tackled with all the force and tactics necessary to use in a regular game, but with little possibility of injury to the player.

Moreover, my dummy is so designed that it may be dressed in regular football uniform so that accurate judgment and co-ordination may be taught. My dummy may be dressed in the opponents' uniform, thereby bringing about a desirable psychological effect upon the player.

The above objects and advantages have been accomplished by the device shown in the accompanying drawing, of which:

Fig. 1 is a front elevation of my device.

Fig. 2 is a side elevation thereof.

Fig. 3 is a rear elevation thereof.

Fig. 4 shows my dummy in a squatting position.

Fig. 5 is a side elevation of the dummy showing it in a running position.

Fig. 6 is an enlarged, fragmentary, sectional view of my dummy.

My dummy comprises an upper part 10, representing the torso of the human body, and formed with an upper protruding portion 11 to represent the chest of a player, and with a concave portion 12 which represents

the portion lying over the abdomen of the human body. Depending from the upper part are two limb parts 13 of my invention, each separately suspended from the upper part 10. Each limb part comprises a thigh portion 14 and a leg portion 15. The material forming the thigh portions is stitched across at 16 where the knee of the player is located, whereby a hinge is formed so that the leg portion 15 may be bent to assume various angular positions with the thigh portion 14.

The upper part 10 of the dummy is made preferably of fabric, leather, or other suitable material, and is stuffed with cork, sawdust, or the like. This part of the dummy is provided with a substantially flat bottom surface 20, arranged substantially at right angles to the back 17 of the upper part 10. This surface is reinforced and retained in its flat condition by a number of slats 18 of semi-rigid material, such as leather, which extend substantially across the bottom, one of them being preferably located at the junction of the back surface 17 with the flat surface 20. These slats are preferably shorter than the width of the upper part so as not to stiffen the working edges thereof, thus avoiding possible injury to the player. A reinforcing strap 21 engages this surface and is passed around the upper part of the dummy, extending up the sides and over the top where it is provided with a loop 22 in which a top ring 23 is disposed. The slats 18 provide a semi-rigid surface for engagement with the strap whereby the upper part retains its normal shape. The strap is preferably stitched to the material forming the dummy and by means of the top ring the dummy may be suspended in a vertical standing position (see Figs. 1-3).

Extending diagonally from the front of the upper part 10 to the back 17 thereof, is an oblique strap 24 having its forward portion located preferably between the chest portion 11 and the concave portion 12. This strap may also be stitched, in the position shown, to the material of the torso 10. A back ring 25 is secured to this strap, whereby the dummy may be suspended or

held in a crouching or running position, as shown in Figs. 4 and 5.

The limb parts 13 are suspended from the upper part 10 of the dummy preferably by means of the material which joins the two parts, and this material extends across the front of the dummy and forms a hinge at 26. Since this hinge is provided only at the front of the dummy, the upper part 10 thereof may be swung forwardly and downwardly or the limb parts 13 may be swung forwardly and upwardly, as shown in Figs. 4 and 5, which is a characteristic of the human body. However, when the substantially flat surface 20 is brought into engagement with the upper surfaces of the thigh portions, stops are provided which prevent the upper part or the limb parts from being swung backwardly in relation to each other, which also simulates this characteristic of the human body.

The limb parts 13 are also made of suitable flexible material and are stuffed with cork, sawdust, or other material of this nature. The leg parts may be formed at their lower ends with slight lateral projections 27 and with a forwardly projecting foot portion 28, whereby shoes may be placed upon the dummy, if desired, together with other clothing, to make it more realistic.

In order that the dummy may be put into a running position, it is desirable to draw one of the leg portions 15 upwardly, as shown in Fig. 5. In order to hold the leg in this position, I employ a resilient member 30 which may be of rubber or a helical spring, and which is attached at one end to a loop 31 secured to the back of the thigh portion 14 and at its lower end to a loop 32 secured to the back of the ankle of the leg portion 14. This resilient member is preferably passed through a loop 33 secured to the lower part of the thigh portion which may be located immediately above the knee.

In some cases it may be desirable to add to the realism of the dummy by supplying arms. In such case a sweater 35, as shown in Fig. 5, may be placed over the upper part 10 of the dummy, the sweater having the lower ends of its sleeves 36 stitched together at 37 and stuffed with suitable material. It will be seen that the sleeves of the sweater shown upon the dummy of Fig. 5 when so stuffed will be suspended from the dummy, thus forming arms in realistic manner.

From the foregoing it will be obvious that my dummy can be placed in the various positions assumed by players in the game of football, and that owing to its construction, when it is tackled, it will react under such tackle in a manner similar to a human antagonist, and thus give to the player all the realism of the game, as well as enabling the instructor to give very specific and minute instruc-

tions, which would otherwise be impossible.

If desired, a flexible strap may be extended down the front of the dummy from the chest portion 11 of the upper part 10 to each of the thigh portions 14, which will serve to prevent the upper part and limb parts from having relative backward swinging movement.

This and other modifications of the details herein shown and described may be made without departing from the spirit of my invention or the scope of the appended claims, and I do not, therefore, wish to be limited to the exact embodiment herein shown and described, the form shown being merely a preferred embodiment thereof.

Having thus described my invention, what I claim is:

1. A tackling dummy comprising an upper part, two limb parts, each comprising a thigh portion and a leg portion, loops carried at the rear of the thigh and leg portions, and resilient means connecting the loops, whereby either leg portion may be drawn up toward the thigh portion.

2. A tackling dummy comprising an upper part, two limb parts suspended from the upper part, each comprising a thigh portion and a leg portion, hinge means connecting the limb parts with the upper part for permitting the limb parts and upper part to swing forwardly, means for preventing such parts from swinging backwardly in relation to each other, loops carried at the rear of the thigh and leg portions, and resilient means connecting the loops, whereby either leg portion may be drawn up toward the thigh portion.

3. A tackling dummy comprising an upper part having a lower, substantially flat surface, two separate limb parts, each independently suspended from the upper part, hinge means extending across only the lower front edge of the upper part and the upper edge of each of the limb parts, each limb part being formed with a surface which coacts with the flat surface of the upper part for preventing such upper part and limb parts from swinging backwardly in relation to each other.

4. A tackling dummy comprising an upper part having a lower, substantially flat surface, two separate limb parts, each independently suspended from the upper part, hinge means extending across only the lower front edge of the upper part and the upper edge of each of the limb parts, each limb part being formed with a surface which coacts with the flat surface of the upper part for preventing such upper part and limb parts from swinging backwardly in relation to each other, and means for reinforcing and stiffening the flat surface of the upper part.

5. A tackling dummy comprising an upper part having a lower, substantially flat surface, two separate limb parts, each independ-

ently suspended from the upper part, hinge means extending across only the lower front edge of the upper part and the upper edge of each of the limb parts, each limb part being 5 formed with a surface which coacts with the flat surface of the upper part for preventing such upper part and limb parts from swinging backwardly in relation to each other, and a back ring arranged at the back of the upper 10 part.

6. A tackling dummy comprising an upper part having a lower, substantially flat surface, two separate limb parts, each independently suspended from the upper part, hinge 15 means extending across only the lower front edge of the upper part and the upper edge of each of the limb parts, each limb part being formed with a surface which coacts with the flat surface of the upper part for preventing 20 such upper part and limb parts from swinging backwardly in relation to each other, and a top ring provided at the top of the upper part.

7. A tackling dummy comprising an upper 25 part, two separate limb parts independently suspended from the upper part, each limb part comprising a thigh portion and a leg portion, a back ring provided at the back of the upper part for suspending the dummy, 30 loops carried at the rear of the thigh and leg portions, and resilient means connecting the loops.

8. A tackling dummy comprising an upper 35 part having a lower, substantially flat surface, two separate limb parts, each independently suspended from the upper part, hinge means extending across only the lower front edge of the upper part and the upper edge of each of the limb parts, each limb part being 40 formed with a surface which coacts with the flat surface of the upper part for preventing such upper part and limb parts from swinging backwardly in relation to each other, and a garment placed over the upper part, said 45 garment having sleeves which are stuffed to simulate arms.

9. A tackling dummy comprising an upper part formed with an upper protruding front portion, and a concave abdominal portion 50 below the protruding portion, two separate limb parts, each independently suspended from the upper part and hingedly attached to the upper part at the front of the dummy only, and means for 55 preventing the upper and limb parts from swinging backwardly in relation to each other.

10. A tackling dummy comprising an upper part, two limb parts suspended from 60 the upper part, each comprising a thigh portion and a leg portion, the thigh portion being formed in simulation of the human thigh, hinge means connecting the limb parts with the upper part for permitting the limb parts 65 and upper part to swing forwardly, means

for preventing such parts from swinging backwardly in relation to each other, loops carried at the rear of the thigh and leg portions, and resilient means connecting the loops, whereby either leg portion may be 70 drawn up toward the thigh portion.

In testimony whereof, I have hereunto signed my name.

VINCENT J. LOUGHLIN.
